(57) **CLAIM**

We claim the ornamental design for a strapping packing machine, as shown and described.

DESCRIPTION

FIG. 1 is a perspective view of a strapping packing machine showing our new design;

FIG. 2 is front plan view thereof;

FIG. 3 is a left side view thereof;

FIG. 4 is a right side view thereof;

FIG. 5 is a top plan view thereof;

FIG. 6 is a bottom plan view thereof; and,

FIG. 7 is a rear plan view thereof.

The broken line showing of environmental structure in FIGS. 1-7 is for illustrative purposes only and forms no part of the claimed design.
